UNITED STATES PATENT OFFICE.

THOMAS DAVID CRAWFORD, OF HAMMOND, INDIANA.

Fixture for Self-Serving Stores.

1,390,673.

Specification of Letters Patent. Patented Sept. 13, 1921.

Application filed October 6, 1920. Serial No. 414,962.

To all whom it may concern:

Be it known that I, THOMAS DAVID CRAWFORD, a citizen of the United States, residing at Hammond, in the county of Lake and State of Indiana, have invented a new and useful Unit Type of Fixtures for Self-Serving Stores, of which the following is a specification.

The object of my invention is to provide an improved type of self-serving stores having a novel unit type of fixtures which permits of the rapid and convenient installation of the store fixtures without their being nailed to the walls or floor of the building so that they may remain the personal property of the occupant of the store and not become a part of the realty which would transfer their ownership to the landlord of the building. It is further my object to provide an improved arrangement of aisles and improved details of construction as disclosed in the accompanying drawings, in which—

Figure 1 is a top plan of a store constructed in accordance with my invention and of sufficient width to provide three main aisles;

Fig. 2 is a transverse section on line 2—2 of Fig. 1;

Fig. 3 is a top plan of my invention installed in a store of relatively narrow width having only two main aisles;

Fig. 4 is an enlarged front elevation of the front railing or partition;

Fig. 5 is a front section on line 5—5 of Fig. 4;

Fig. 6 is a horizontal section on line 6—6 of Fig. 4;

Fig. 7 is a horizontal section on line 7—7 of Fig. 4;

Fig. 8 is a detail front elevation of the shelving, partly in to show the means for fastening adjacent units together;

Fig. 9 is a transverse vertical section of the shelving on line 9—9 of Fig. 8;

Fig. 10 is a horizontal section on line 45 10—10 of Fig. 8;

Fig. 11 is a detail top plan of the shelving;

Fig. 12 is a detail perspective view of one of the shelves mounted in the supporting 50 rack bars;

Fig. 13 is a top plan of a modified arrangement of store units showing the means for connecting them together in such arrangement;

55 Fig. 14 is a side elevation of the basket rack;

Fig. 15 is a top plan of the same;

Fig. 16 is a transverse vertical section of the basket rack; and

Fig. 17 is an enlarged detail sectional view of the trap mechanism for opening the entrance door to the store aisles.

Like numerals designate like parts in each of the several views.

Referring to Figs. 1 and 3 of the accompanying drawings, I provide a suitable front railing or partition 2 spaced back a suitable distance from the main entrance door 1 of the store building. This front partition or railing is provided with a suitable inwardly opening entrance door 3 which is automatically operated by the weight of the customer as he steps on the trap 4 in front of the door, permitting him to enter and select a suitable basket from 75 the basket rack 5, and thence pass down the main entrance aisle 6 to the rear aisle 7 from which he may pass down the outside aisle 9, or if the store is of the type shown in Fig. 1, down either aisle 9 or central aisle 80 8. I provide a flour bag counter 10 at the front end of the shelving 19. Where there is an intermediate aisle 8 I provide a passage 11 between such intermediate aisle and the outer aisle 9. Should the store be of 85 sufficient width it is within the contemplation of my invention to provide a plurality of similar intermediate aisles 8 and passageways 11. I provide a suitable bundle counter 13 adjacent the passageway 12 which 90 opens into the exit passage 15, leading past the cashier's desk 14 to the outwardly swinging door 16. I provide a suitable open face refrigerator 17 from which the clerk at the counter 13 may obtain for customers articles 95 they may select. I also provide a table 18 for general use near the entrance of the store.

Referring to Figs. 1 and 3, I provide a series of shelvings 20 along the sides of the 100 store and one or more series of shelvings 19 intermediate between the shelvings 20. I further provide the rear shelving 21 having suitable rear doors 22 opening into a stock room 23 provided with suitable table 24 and other necessary equipment. I provide suitable mirrors 25 mounted on the top of the rows of shelvings 20 at a suitable angle to enable the clerk at the counter 13 to obtain a general view of the main aisles.

Referring to Figs. 4 to 7, the front partition 2 is supported by a suitable grooved

foot rail 26 which is secured to the floor by screws and reinforced by the floor braces 33 which are attached to the upright posts 27. The posts 27 are provided with vertical channels 26 to receive the frame portions of the panels 29, which panels are provided with upper screens 30. I provide a horizontal rail 31 which is attached by bolts 32 to the upright posts 37.

10 Referring to Figs. 8 to 11, illustrating in detail my unit construction of shelving, I provide a series of shelving, each unit consisting of a rear wall 35, side walls 34, a floor or bottom wall 42, and a top 36. I 15 further provide upright rack bars 38 extending the entire vertical length of the inside of the shelving and having suitably spaced notches 39 adapted to receive and support the removable cross bars 40 which 20 in turn support the adjustable shelves 41, as shown in Fig. 12. These shelves are removable, permitting their arrangement at any desired height.

Adjacent units of shelving are secured together longitudinally by suitable bolts 43, as shown. The series of intermediate shewings 19 are secured back to back by suitable U-shaped links 44 which may be inserted in any of the correspondingly spaced 30 openings 45, as shown in Figs. 9 to 11.

Referring to Fig. 13 I provide suitable end clips 46 which may be bent at any desired angle for securing the ends of shelving units together where the shelving is arranged in semi-circular or in other arrangements where the units of the shelving are disposed at an angle to each other.

Referring to Figs. 14, 15 and 16, the basket rack 5 is provided with slatted sides 47 and slatted ends 49 and a slatted bottom 46, and a suitable rack 50.

Referring to Fig. 17 there is illustrated a detail sectional view of the trap door 4 which on being depressed lowers and releases the catch 51, permitting the door to be automatically swung open by the spring 55 (Fig. 1). The trap door 4 is maintained in its normally raised and door-locking position by the spring 52 which encircles the bolt 53, bearing on the washer 54.

The main purpose of my invention is to provide the novel type of shewings which are adapted to be readily set up in the manner shown, which are not attached to the walls of the building at all and are only releasably attached to the floors in the manner described, thus permitting the store fixtures to remain the personal property of the one who installs them. All units of the shelving are of a like unit size and are provided with like spaced openings for their convenient attachment by the fastening devices 43, 44 and 46 in whatever position the shelving may be set up. The basket bin, the flour rack, the counter and the front

partition or railing and also all passageways and main aisles are of sizes that are equal to or usually a multiple of the size of one unit of the shelving. If the width of the store is a multiple of the unit sizes of the shelving adopted, the shelving will fit snug against the side walls; if it is not an exact multiple of the unit size of the shelving the unit measurements will be maintained in laying out the aisles, etc., and the side shelving 20 will be set away from the walls the necessary number of inches to maintain the multiple unit measurements of aisles and shelving transversely of the store, thus an aisle will be a certain multiple of the width of the shelving in all instances. I have dispensed with the use of turnstiles as I have found that a trap door of the type illustrated in my drawings permits the use of a narrow entrance passage and at the same time permits the more rapid entry of customers than does a turnstile. For the exit passage no turnstile is necessary since the customers are under surveillance of the cashier as they pass out through passage 15. By providing the connecting passage 11 between main aisles I afford the customer means of more expeditious passage through the store in case he does not care to inspect the entire stock of goods. My shewings are different from other sectional cases in that they are all fastened together by the novel U-shaped links 44 which are readily inserted in the openings 45, and are equally useful when the units of the shelving are arranged in staggered arrangement if such arrangement is desired. The openings 45 are disposed about four inches apart, starting about two inches from the end of each unit of shelving. The series of shewings illustrated in Fig. 9 are eight inches deep and ten inches high, which dimensions are illustrative of what I have found a desirable size of unit construction. Links 44 are made close enough to bind tightly and are driven in place. Where cases are arranged at an angle to each other, as shown in Fig. 13, their ends are secured together by suitable clips 46 and these clips may be flexed to suit any angle at which the cases may be arranged.

It is within the contemplation of my invention to adapt the shelving to an extremely narrow store by arranging the refrigerator 17, the counter 13, and the flour rack 10 longitudinally instead of transversely of the length of the store. The unit type of fixtures described permits of an adaptation of my shelving to any store building regardless of its shape and permits the utilization of extremely narrow rooms for the installation of self-serving stores.

What I claim is:

1. In store fixtures of the class described, the combination of duplicate shelving cases,

said cases having a series of like spaced openings in aligned portions of the rear part of their top walls, and links insertible in adjacent openings, the openings being spaced 5 a like distance apart, and the cases being securable back to back, the desired relation, at will.

2. In a unit type of fixtures for self-serving store, series of detachable shelving 10 cases arranged to form aisles for the pas-

sage of customers, said cases being of unitary size, fastening means for securing the ends of aligned cases together, independent removable fastening means for securing intermediate rows of shelving cases firmly together back to back, separate doors for the entrance and exit of customers, and all of said doors being a multiple of the size of the cases. 15

THOMAS DAVID CRAWFORD.
